(57) **CLAIM**

The ornamental design for a ring sizer, as shown and described.

DESCRIPTION

FIG. 1 is a top isometric view of a narrow-band embodiment of a ring sizer showing our new design;

FIG. 2 is a bottom isometric view of the narrow-band embodiment;

FIG. 3 is a bottom view of the narrow-band embodiment;

FIG. 4 is a top view of the narrow-band embodiment;

FIG. 5 is a front view of the narrow-band embodiment, the rear view being identical;

FIG. 6 is a right side view of the narrow-band embodiment, the left side view being identical;

FIG. 7 is a top isometric view of a medium-band embodiment of a ring sizer showing our new design;

FIG. 8 is a bottom isometric view of the medium-band embodiment;

FIG. 9 is a bottom view of the medium-band embodiment;

FIG. 10 is a top view of the medium-band embodiment;

FIG. 11 is a front view of the medium-band embodiment, the rear view being identical; and,

FIG. 12 is a right side view of the medium-band embodiment, the left side view being identical.

The broken lines shown represent unclaimed subject matter and form no part of the claimed design.
